SAFETY AIRPLANE

Filed Oct. 14, 1929

FIG. 1

FIG. 2

FIG. 3

Margaret Cheetham
INVENTOR.

BY

C. A. Harman

ATTORNEY.

UNITED STATES PATENT OFFICE

MARGARET CHEETHAM, OF YOUNGSTOWN, OHIO

SAFETY AIRPLANE

Application filed October 14, 1929. Serial No. 399,505.

This invention relates to airplanes and more especially to safety devices attached to airplanes for the purpose of providing auxiliary wings that may be opened from 5 a folded position when it is found necessary to make a forced landing, or when it is desired to make a landing at reduced speed.

The main object of this invention is to provide a pair of auxiliary wings carried in 10 a folded position above a regularly equipped wing or wings and in a general position, parallel to said regular wings.

Another object of the invention is to provide flexible cables to hold the auxiliary 15 wings in a proper position when opened.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

The invention is illustrated in the accompanying drawings, wherein:—

Figure 1 is a partial top plan view of the device.

30 Figure 2 is a side elevation of the device. Figure 3 is a section taken on line 3—3 of Fig. 2.

By referring to the drawings it will be seen that there is provided a body 1. This body 35 1 is provided with regular equipped wings 2 and 3. In order to provide sufficient support means for the auxiliary folding wings, I have provided perpendicular support members 4, 5, 6, and 7. These support members 40 are located and secured in reference to the body 1 in a central portion and in alignment with each other. Attached to the upper end of each of said support members there is provided a central rod 8, to which 45 is attached in a hinged manner, a plurality of arms 9. At the outer end of the arms 9 there is a securing rod 10. It is understood that the airplane is equipped with a similar wing equipment on the other side, so that 50 the auxiliary wings may be folded when not

in use. When being folded the arms 9 swing with the rod 10 ahead, due to the hinge connections at points 11 and 12.

By referring to Fig. 3 it will be seen that one of the auxiliary wings is folded while the other wing is shown opened. In order to provide a sufficient support for the auxiliary wings when they are opened there is provided a cable 13, which is attached to an outer edge of the auxiliary wings at a point 14 and to the body at a point 15. By referring to Fig. 2 it will be seen that there is a rear cable 16 attached to the securing rod 10 at a point 17 and to the body 1 of the airplane at point 18. It is obvious that these cables 13 and 16 may be held under tension by any suitable means so that the same is always under tension when opened or closed.

Secured to the securing rod 10 there is provided a flexible covering 19. This is secured by means of stitches 20 to outer perimeter of the auxiliary wings. In order to keep the flexible covering 19 from bagging there is provided a plurality of reinforcing cords 21 which are secured to the securing rod 10 at points 22.

In order to hold the auxiliary wings in a folded position there is provided a catch 23 at an extreme front end 24 of the securing rod 10. There is provided a releasing cord 25 for the purpose of releasing the catch 23 when it is desired to open the wings. In order that the wings may swing open there is provided a curved spring 26 which is secured to the front arm member 9 so that when the catch 23 is released, the curved spring 26 starts to open the wings which is completed by the force and friction of the air as the plane moves ahead. It will also be seen that there is provided a cable 27 which is secured to the central rod 8 at a point 28 and a point 29 on the securing rod 10, for the purpose of holding the wing in a desired open position.

What I claim is:—

1. In a device of the class described, a pair of folding auxiliary wings, said wings provided with a central rod, a plurality of supports for said central rod, a plurality of

arm members attached to said central rod, outer ends of said plurality of arms hinged to an outer securing rod, a flexible covering for said wings, a plurality of reinforcing cords positioned above said covering of wings, means which holds said auxiliary wings in a folded position, a spring means for starting the opening of said wings, substantially as described.

5 2. In a device of the class described, a plurality of perpendicular support members in alinement with each other and positioned centrally with reference to an airplane body, a pair of auxiliary wings secured to said support, means for folding said wings and means of releasing said wings from a folded position in order that they may swing and be held in a open secured position, substantially as described.

10 20 In testimony whereof I affix my signature.
MARGARET CHEETHAM.
